UNITED STATES PATENT OFFICE.

JOSEPH ALBERT RONCHETTI, OF WOONSOCKET, RHODE ISLAND, ASSIGNEE, BY MESNE
ASSIGNMENTS, TO THE NOISELESS TYPEWRITER COMPANY, OF MIDDLETOWN,
CONNECTICUT, A CORPORATION OF CONNECTICUT.

TYPE-WRITING MACHINE.

1,120,976.

Specification of Letters Patent. Patented Dec. 15, 1914.

Application filed June 5, 1908. Serial No. 436,753. Renewed May 14, 1914 Serial No. 838,617.

To all whom it may concern:

Be it known that I, JOSEPH A. RONCHETTI, a subject of the King of Italy, residing at Woonsocket, in the county of Providence, 5 and State of Rhode Island, have invented certain new and useful Improvements in Type-Writing Machines, of which the following is a full, clear, and exact description; such as will enable others skilled in the art 10 to which it appertains to make and use the same.

This invention relates to that class of typewriting machines wherein the type carriers are provided with two or more types 15 and wherein the platen is normally held in position to receive imprints from one of the sets of type, the type carrier and the platen being relatively shiftable to enable the latter to receive imprints from the other set or 20 sets of type.

One of the objects of the present invention is to provide improved means for shifting the platen to positions at either side of a normal central position, so as to enable the 25 same to receive impressions from any one of three types mounted upon each type bar.

Another object thereof is to provide simple and efficiently operating means for shifting the platen carriage, such that, 30 while the platen is always locked and firmly held in a normal central position, the locking means will not in anywise interfere with its being readily shifted to other printing positions.

Another object is to provide mechanism for arresting the shifting movements of the platen without any impact or concussion between the relatively movable parts.

A further object is to provide improvements generally over the platen shifting mechanism which forms the subject matter of my application, Serial No. 380,601, filed June 24, 1907.

Other objects will be in part obvious 45 and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings, wherein is illustrated one of the various possi-

bodies of my invention, Figure 1 is 55 a plan view of the platen carriage shifting mechanism, the carriage and associated parts of the machine being omitted in the interest of clearness of illustration: Fig. 2 is a sectional view taken transversely of 60 the machine on line 2—2, Fig. 3, the shifting mechanism being shown in elevation: Fig. 3 is a rear elevation, looking toward the right hand side of Fig. 2; Fig. 4 is a view taken on line 4—4 of Fig. 3, looking 65 in the direction of the arrow; Fig. 5 is a fragmentary view of one of the locking devices for a shift lever, the parts being shown in a position different from that in which they are shown in Fig. 2; Fig. 6 is a side 70 view of the lower portion of the mechanism shown in Fig. 2, showing one of the shift levers in a depressed position; and Fig. 7 is a view of a portion of the mechanism shown in Fig. 3, and illustrating the 75 positions assumed by the parts when the platen carriage has been shifted upwardly from its normal intermediate position.

Similar reference characters refer to similar parts throughout the several views 80 of the drawings.

Referring now to the drawings, wherein my invention is shown applied to a typewriting machine of the front strike type, 1 denotes a portion of the framing of the 85 machine, 2 indicates a bed upon which is supported a bank of types, one of which is shown at 3, said type bars being adapted to be projected against a common printing point upon the platen, which is shown conventionally at 4. The type bars, in the present instance, are provided with three type characters and are projected to the impression points of the platen by suitable actuating mechanism not shown herein. The platen 4, in the present instance, is supported in a platen carriage 5 which rests at its rear portion against an upwardly extending member or horn 6 of a center tie-rod 7 which extends fore and aft of the 100 machine and is anchored in the front wall thereof by means not shown herein, said tie-rod being guided and supported underneath bed 2 in a way 8 and being also supported at 9 upon a way or slide provided 105 upon the side wall of the machine. Tie-rod 7 is adapted to be moved forward or backward to change the position of the

platen with respect to the faces of the types.

The platen carriage, in the present instance, is provided with rails 10 and 11 between which is positioned an oscillatory ball-rail 12, the latter being carried upon swinging arms 13 which are carried upon a rock shaft 14 journaled in brackets 15 formed upon the diebed. Rail 12 is adapted to be shifted vertically in opposite directions to shift the platen carriage in corresponding directions, and the opposite ends of said rail are caused to move laterally distances when shifted by means of the rock shaft 14 and arms 13. This latter mechanism, however, forms no part of my present invention, but forms the subject matter of my application, Serial No. 436,552, filed of even date herewith.

Depending from rail 12, and fastened thereto in the central portion thereof, is a bracket 16 in which is formed a socket adapted for receiving a ball 17 formed upon a rod 18, said ball being held in position within said socket by means of a plate 20 which is secured to bracket 18, as by means of adjusting screws 21. Plate 20 may be adjusted relative to bracket 18 in order to take up any slack which may exist in the ball and socket joint, by means of the screws 21. Rod 18 at its lower end is provided with a ball 22 which is received in a socket 23 formed in a swinging lever 25 and is maintained in said socket by means of a socketed plate 26 which is adjustably secured to plate 23, as by means of clamp screws 27. Lever 25 has one end attached to a fixed portion 28 of the frame of the machine, by means of a ball and socket 29, the parts of which are adjustable to take up slack, and has its other end connected, as by means of a ball and socket joint 31, to a floating lever 32. Floating lever 32, in the present instance, is of double or duplex form, being constituted by two bars 33 and 34 joined together at their rear ends at 35. Floating lever 32, intermediate its ends, is pivotally connected by means of a pivot bolt 36 with a shift lever 37 which extends between members 33 and 34, and is pivoted at 38 upon a bracket 39 extending upward from the base of the machine. Another shift lever 41 is pivotally connected to the forward end of the floating lever 32, by means of a pivot bolt 42, elongated slots 43 being provided in the forward ends of members 33 and 34 which constitute the floating lever through which bolt 42 extends. Shift lever 41 also extends between members 33 and 34 of the floating lever and is pivoted at 44 upon bracket 10. A clip or bracket 45, adjustably mounted upon floating lever 32, intermediate its points of pivotal connection with the shift levers, and held in adjustable position thereon or by means of a set-screw 46, is connected

with a retractile spring 47 which urges it in upward position and likewise urges the shift levers 37 and 41 to an upward position against a fixed cushion stop 48. Spring 47, therefore, holding the shift levers in normal positions of rest against stop 48, also operates to restore the platen carriage to its normal central position when the same has been shifted in either direction therefrom.

Each of shift levers 37 and 41, in the present instance, is provided with forwardly extending finger portions or levers 50 and 51 which are notched thereto at 52 and 53, respectively. These finger levers lie in contact with the lateral sides of the forward ends of the shift levers and are provided with notched portions 54 and 55 to receive tongues or projections 56 and 57 formed upon the forward ends of the shift levers.

It will be observed from an inspection of Figs. 2, 3 and 6 of the drawings that the finger levers 50 and 51 are constructed slightly wider than the tongues which they receive in order to provide for a slight relative movement between the finger levers and the shift levers, the engagement of the tongues with the walls of the notches operating to limit such relative movements. Finger levers 50 and 51 extend forward and then upwardly and in their upper ends are equipped with 58 finger levers 58 and 60. Finger levers 50 and 51 are held in an upward position by means of leaf springs 61 and 63, respectively, attached to the key levers and having their free end, emerging with said finger levers, as clearly shown in Fig. 6 of the drawings.

Shift levers 37 and 41 are locked in their raised positions by means of springs, one of which is shown at 62, said spring being attached, as by means of a screw 64, to the rearward of the machine and extending upwardly beneath a lug or abutment 65 formed upon the shift lever. These springs are adapted to be moved from beneath said abutments by means of depending portions 66 and 67 provided upon finger levers 50 and 51, respectively. It will be understood that upon a depression of one of the shift levers, the depending portions 66 or 67 thereof will engage with one of springs 63 and 65, swing the same from beneath the abutment of the particular shift lever depressed, the other of said springs remaining in engagement with the abutment of the other of the shift levers and holding it against depression. Each shift lever is, therefore, locked in a raised position while the other thereof is depressed to swing the floating lever to shift the platen carriage, and the pivotal connection of the shift lever which is held in its locked position operates with the floating lever as a stationary fulcrum upon which said floating lever swings.

Pivotedly attached near the end of the swinging lever 25, as by means of a pivot 126

screw 68, is a link 70 which is similarly attached at 71 to a second link 72. Link 72 is rotatively mounted at 73 upon an adjustable eccentric 74 which is clamped, as by 5 means of a clamp-screw 75, in a bracket 76 formed upon the framework of the machine. Eccentric 74 may be adjusted to any desired position in said bracket and clamped in said position by means of screw 75, as will be 10 understood. Lever 25 is similarly connected by links 77 and 78 pivotally connected at 80 to an adjustable eccentric which is adapted to be adjusted in a support 82 and clamped therein, as by means of a clamp- 15 screw 83. Retractile springs 84 and 85 are connected with links 70 and 77, respectively, said springs being attached at their other ends, as at 86 and 87, with the swinging lever 25. These springs tend to flex the 20 links and hold them in the position shown in Fig. 3 of the drawings. Whenever lever 25 is swung through its connection with the shift mechanism to lift or depress the platen carriage, one pair of these links will 25 straighten, as shown in Fig. 7 of the drawings, and when said links have been moved into alinement, as shown, the swinging lever will have reached its limit of movement, and said lever and the associated parts will, 30 therefore, be arrested without impact or concussion and, therefore, noiselessly.

The platen carriage is balanced, in the present embodiment of my invention, by means of a full elliptic spring 88 which is 35 positioned beneath the lever 25 and attached to a depending portion 90 of rod 18, said spring being supported upon an adjusting screw 91 threaded in a bracket 92 formed upon the framing of the machine. The tension of this spring is such that the carriage will normally be held in central position, but may be readily moved in either direction from such position when the same is shifted.

45 Having thus described this embodiment of my invention, the operation thereof may now be understood. Assuming the parts to be in normal position, as shown in Fig. 2 of the drawings, a depression of either of the 50 shift keys 58 or 60 will first, as above described, move the locking spring from underneath the abutment formed upon the shift lever, thereby allowing a free depression of the shift lever, the other shift lever 55 remaining in locked position, and the pivotal connection thereof with a floating lever 32 forming a stationary fulcrum upon which said floating lever swings under compulsion of the lever being depressed. The swinging 60 of floating lever 32 will cause lever 25 to swing upward or downward in accordance with the particular shift lever depressed, and, through rod 18, cause a corresponding movement of the platen, such movement, as 65 above described, being limited by the

straightening of the toggle comprised by either pair of pivotally connected links. The platen in either of its shifted positions is returned to normal position by means of spring 47, attached to the floating lever 32, 70 which also operates to return the shift levers to their normal position against stop 48.

It will accordingly be seen that I have provided mechanism well adapted to attain, among others, all the objects and aims of my invention in an exceedingly simple, yet efficient, manner. The duplex construction of the floating lever employed herein insures against racking or binding of the connected parts and provides an easy shift action. Moreover, the locking mechanism for the shift levers is simple in construction, and, therefore, is not liable to become easily deranged. The means employed to arrest the shifting movements of the carriage herein is of simple construction and performs its functions without any impact or concussion and, therefore, without the production of noise.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

Having described my invention, what I claim as new and desire to secure by Letters Patent is:—

1. In a typewriting machine, the combination with a platen shiftable in opposite directions from a normal intermediate position, of a double armed lever connected therewith, and a pair of shift levers interposed between said double armed lever, each of which has a pivotal connection therewith and is adapted to move the same in a direction opposite to that in which it is moved by the other, whereby the platen may be shifted in opposite directions from its normal printing position.

2. In a typewriting machine, the combination with a platen shiftable in opposite directions from a normal intermediate position, of a lever comprising a pair of connected spaced members connected with the platen, a pair of shift levers interposed between the members of said first-mentioned lever, each of which has a pivotal connection therewith and is adapted to swing the same in a direction opposite to that in which

- it is shifted by the other thereof, whereby the platen may be shifted in opposite directions from its normal printing position, and means for restoring the platen to normal position.
3. In a typewriting machine, the combination with a shiftable platen normally held in an intermediate printing position, of means for moving said platen to either side of said normal position for different case printing, comprising a pair of shift levers, and a lever having a portion thereof disposed to either side of said shift levers, pivotally connected to each of said shift levers and having a connection with the platen.
4. In a typewriting machine, the combination with a shiftable platen normally held in an intermediate printing position, of a pair of shift levers for raising or depressing the platen to other printing positions, and a double lever common to both of said shift levers and having a portion disposed at either side of said shift levers, said double lever being pivotally connected to each of said shift levers, connected with the platen and adapted to raise or depress the same in accordance with the particular shift lever depressed.
5. In a typewriting machine, the combination with a shiftable platen normally held in an intermediate printing position, of a pair of shift levers, a lever having a portion disposed at either side of said shift levers and connected at different points with each of said shift levers, and means for connecting said lever with the platen, said lever being adapted to swing upon either of its points of adjustment with the shift levers as a fulcrum to shift the platen to either side of its normal position.
6. In a typewriting machine, the combination with a shiftable platen normally held in an intermediate printing position, of a pair of shift levers, and a lever having a portion disposed at either side of said shift levers with which both of said shift levers are pivotally connected at different points in the length thereof, said lever being connected with the platen, the pivotal connection of said lever with one of said shift levers operating as a stationary fulcrum when the other of said shift levers is depressed.
7. In a typewriting machine, the combination with a shiftable platen, of a pair of shift levers, and a lever comprising a pair of spaced connected members pivotally connected at a different point in its length with each of said shift levers and also connected with the platen, said lever being adapted to swing upon either of its points of connection with the shift levers as a fulcrum when the other of said shift levers is depressed.
8. In a typewriting machine, the combination with a shiftable platen, of a pair of shift levers, and a duplex lever having a portion disposed to either side of said shift levers and connected therewith at different points in its length and also connected with the platen, said duplex levers being adapted to swing upon its pivotal connection with one of said shift levers as a fulcrum to shift the platen in one direction from its initial position when the other shift lever is depressed and to swing upon its pivotal connection with the second lever as a fulcrum when the first lever is depressed, whereby the platen will be shifted in another direction.
9. In a typewriting machine, the combination with a shiftable platen, of a duplex lever connected therewith and adapted to shift the same in opposite directions from an intermediate printing position, and a pair of shift levers interposed between the members of said duplex lever, each of which is pivotally connected to the members of said lever at a different point in the length of said lever, the pivots connecting said lever with the shift levers acting as stationary fulcrums or as points of application of power to swing said lever, whereby the platen will be shifted in a direction dependent upon the particular shift lever depressed.
10. In a typewriting machine, the combination with a shiftable platen adapted normally to rest in an intermediate printing position, of a duplex lever connected therewith, a shift lever interposed between the members of said duplex lever and pivotally attached thereto, and a second lever interposed between the members of said duplex lever and pivotally attached thereto at a different point in its length, the pivotal connection of one of said levers operating as a stationary fulcrum about which said lever swings when the other shift lever is depressed to shift the platen.
11. In a typewriting machine, the combination with a shiftable platen adapted to be shifted to either side of a normal printing position for upper or lower case printing, of a pair of shift levers, a lever pivotally connected to each of said shift levers and having a connection with the platen, and a spring member for holding one of said shift levers stationary when the other is depressed, whereby the pivotal connection with the lever connected therewith operates as a stationary fulcrum upon which the latter swings to shift the platen.
12. In a typewriting machine, the combination with a platen adapted to be shifted to either side of a normal printing position for upper or lower case printing, of a pair of shift levers, a lever pivotally connected to each of said shift levers and having a connection with the platen, and a spring-locking member interposed in the path of each of said shift levers and adapted to hold the same stationary during a depression.

- sion of the other, whereby the pivotal connection of each of said shift levers with said second lever operates as a stationary fulcrum about which the latter swings to shift the platen.
- 5 13. In a typewriting machine, in combination, a shiftable platen, a pair of shift levers, a lever connected to each of said shift levers and also the platen adapted to be 10 swung upon its pivotal connection with one of said shift levers about the other thereof when the same is depressed, whereby the platen is shifted, and a spring-locking member disposed beneath each of said shift levers which is automatically removed from locking position when the shift lever is depressed.
- 10 14. In a typewriting machine, in combination, a shiftable platen, a shift lever connected therewith, and a spring member for automatically locking the same in its raised position adapted to be engaged by said shift lever and moved from its locking position when the same is depressed.
- 15 15. In a typewriting machine, in combination, a shiftable platen, a shift lever connected therewith, a spring member mounted upon a fixed portion of the framing of the machine and disposed in the path of said shift lever, whereby the same is locked in its raised position, and means connected with said shift lever adapted to move said spring to an unlocking position when the shift lever is depressed.
- 20 16. In a typewriting machine, the combination with a shiftable platen, of a pair of shift levers connected therewith and adapted to shift the same in opposite directions from a normal intermediate position, and a spring locking member positioned beneath each of said shift levers and adapted normally to hold each thereof in a raised position, each of said spring-locking members being moved to an unlocking position when its shift lever is actuated to shift the platen.
- 25 17. In a typewriting machine, the combination with a shiftable platen, of a two-part shift lever connected therewith, the parts of said shift lever being capable of a limited relative movement, and a spring-locking member carried by a fixed portion of the framing of the machine and positioned beneath said shift lever and adapted normally to hold the same in a raised position, one of the parts of said shift lever when the same is depressed being adapted to engage with said spring-locking member and move the same to an unlocking position.
- 30 18. In a typewriting machine, the combination with a shiftable platen, of a shift lever connected therewith, said shift lever comprising two members swiveled to each other and capable of a limited relative movement, a spring-locking member supported in a fixed portion of the machine and posi-
- tioned beneath said shift lever and adapted to lock the same in a raised position, one of the parts of said shift lever when the same is depressed being adapted to move relatively to the other to engage said spring locking member and move the same to an unlocking position.
- 35 19. In a typewriting machine, the combination with a shiftable platen, of a shift lever connected therewith, said shift lever having a finger extension journaled thereon and capable of a limited movement relative thereto, and a locking member carried by a fixed portion of the framing of the machine and positioned beneath said shift lever and adapted to lock the same in its normal position, said finger extension of said shift lever when the latter is depressed being adapted to engage with and move said locking member to an unlocking position.
- 40 20. In a typewriting machine, the combination with a shiftable platen, of a pair of shift levers connected therewith, an abutment formed upon each of said shift levers, a pair of locking members carried by a fixed portion of the machine, each of which is disposed beneath one of said abutments, whereby said shift levers are normally locked in their raised position, and means carried by each of said shift levers adapted to engage and move said locking member from beneath said abutment when the shift lever is depressed.
- 45 21. In a typewriting machine, in combination, a shiftable platen adapted to be shifted to either side of a normal printing position for upper or lower case printing, a pair of shift levers, a lever pivotally connected to each of said shift levers and having a connection with the platen, a finger lever hinged to each of said shift levers and having a limited swinging movement thereon, an abutment formed upon each of said key levers, a locking member interposed in the path of movement of each of said abutments and adapted in conjunction therewith to lock the key lever in a raised position, and a member provided upon each of said finger levers adapted to engage said locking member and move the same from beneath said abutment when said finger lever is depressed.
- 50 22. In a typewriting machine, the combination with a shiftable carriage, of a lever pivotally supported in the rear of the machine and extending longitudinally of the carriage, a universal connection between said lever and said carriage, a pair of shift levers, and a second lever connecting said first lever with each of said shift levers, said shift levers when depressed being adapted to shift the platen to either side of a normal position for different case printing.
- 55 23. In a typewriting machine, the com-

22. In a typewriting machine, the combination with a shiftable platen carriage normally held in intermediate position but adapted to be shifted to a position on either side thereof for different case printing, of means for shifting the platen comprising a pair of shift levers, a lever connected to each of said shift levers, a second lever pivotally supported in the rear portion of the machine and having a connection with said first lever, a rod which furnishes an actuating connection between said second lever and the carriage, a universal joint for said rod mounted upon said second lever, a universal joint for said rod mounted upon said carriage, and a balancing spring for the carriage supporting said second lever.
23. In a typewriting machine, the combination with a platen carriage which is normally held in an intermediate position but which is adapted to be shifted to a position at either side thereof for different case printing, of means for shifting said platen carriage to either side of its intermediate position comprising a pair of shift levers, a floating lever pivotally connected to each of said shift levers, a lever pivoted at one end upon a fixed pivot and having a connection at its opposite end with said floating lever, means connected with said last-mentioned lever and said platen carriage, a spring positioned beneath said shift lever for balancing the carriage, and means for adjusting the tension of said spring.
24. In a typewriting machine, the combination with a platen carriage which is normally held in an intermediate position comprising a pair of shift levers, a floating lever pivotally connected to each of said shift levers, a lever pivoted at one end upon a fixed pivot and having a connection at its opposite end with said floating lever, means connected with said last-mentioned lever and said platen carriage, a spring positioned beneath said shift lever for balancing the carriage, and means for adjusting the tension of said spring.
25. In a typewriting machine, the combination with the vertically-shiftable carriage which is normally held in intermediate position, of means connected with said carriage and adapted to shift the same comprising a pair of shift levers extending transversely of the machine and pivoted in the rear portion thereof, a floating lever pivotally connected with each of said shift levers, a second lever pivoted in the rear portion of the machine and having its opposite end connected with said floating lever, and a rod interposed between said second lever and said carriage and connected to each of said parts by a universal joint.
26. In a typewriting machine, the combination with a shiftable platen carriage normally supported in an intermediate position but adapted to be shifted vertically in opposite directions from such position for different case printing, of means for shifting the platen comprising a pair of shift levers extending transversely of the machine and pivoted in the rear portion thereof, a duplex floating lever having a portion disposed at either side of said shift levers and pivotally connected at a different point in its length with each of said shift levers, a second lever pivoted to the rear portion of the machine, a universal joint for connecting said lever with said floating lever and the

platen carriage, universal joints located upon said platen carriage and upon said second lever for the opposite ends of said rods, means for taking up slack in said universal joints, and a full elliptic spring 70 positioned beneath said second lever and an adjustable support for said spring.

27. In a typewriting machine, the combination with a shiftable platen carriage normally held in an intermediate position 75 but shiftable in opposite directions therefrom for different case printing, a pair of shift levers, a swinging lever swiveled in a fixed portion of the machine, operatively connected with said shift levers and adapted to be swung in opposite directions thereby, a rod interposed between said lever and said platen carriage, a ball and socket joint mounted upon said lever for one end of said rod, a ball and socket joint mounted 85 upon said platen carriage for the other end of said rod, means for taking up slack in said ball and socket joints, a spring positioned beneath said lever and adapted through the connection therewith with the 90 platen carriage to counter balance the latter, and an adjustable support for said spring.

28. In a typewriting machine, the combination with the shiftable platen carriage, 95 of means for shifting the same from a normal printing position to another printing position, and a stop for determining the shifted position of the carriage comprising a pair of pivotally connected members, one 100 of which is mounted upon an eccentric support and the other of which is connected with the carriage.

29. In a typewriting machine, the combination with a shiftable carriage, and means 105 for shifting the same from a normal printing position to another printing position, of a stop for arresting the movement of the carriage when the same is shifted, comprising a pair of links pivotally connected together and 110 adapted normally to lie in a flexed position, one of said links being connected with the carriage, and an eccentric support for the other of said links.

30. In a typewriting machine, the combination with a shiftable carriage and means 115 for raising or depressing said carriage to carry the platen to a printing position located at either side of a normal intermediate position, of stops for arresting the 120 shifting movements of the carriage, comprising two pairs of pivotally connected links, one link of each pair being connected with the carriage, and an adjustable eccentric support for the other link of each pair 125 mounted upon a fixed portion of the framing of the machine, each pair of links normally lying in a flexed position and arresting the movement of the carriage when straightened.

31. In a typewriting machine, the combination with the platen carriage normally held in intermediate position and adapted to be shifted to either sole of such position for different case printing, of means for shifting the platen carriage, and means for arresting the movement thereof at its shifted positions comprising two pairs of oppositely disposed, pivotally connected links, one link of each pair being connected with the platen carriage, fixed eccentric supports for the other links of said pairs, and a spring for normally urging said links to fixed positions, each pair of said links when straightened being adapted to arrest the movement of the platen carriage.

32. In a typewriting machine, the combination with the platen carriage which normally rests in an intermediate position and is shiftable in opposite directions therefrom for different case printing, of a swinging lever operatively connected with the carriage, shift mechanism operatively connected with said swinging lever, two pairs of pivotally connected links one link of each pair being pivotally connected with the swinging lever, an adjustable eccentric support for each of the other links of said pairs, and a spring interposed between said lever and each of said pairs of links for normally urging them to fixed positions, said links when straightened operating to arrest the

shifting movements of the carriage in either direction.

33. In a typewriting machine, the combination with a movable part, means for silently arresting and limiting the movement of said movable part comprising a pair of pivotally connected links normally lying in flexed position, one of said links being pivotally connected with said movable part and the other being pivotally connected with a relatively fixed portion of the machine and eccentric means associated with one of said pivotal points of connection adapted to adjust the length of travel of said movable part.

34. In a typewriting machine, the combination with a shiftable carriage, a member pivotally supported in the rear of the machine and extending longitudinally of the carriage, means connecting said member and said carriage having a universal connection with one of said parts, and a shiftable lever connected with said first mentioned means adapted to shift the carriage from a normal position when actuated.

In testimony whereof I affix my signature, in the presence of two witnesses.

JOSEPH ALBERT RONCHETTI.

Witnesses:

L. H. WILSON,
R. M. SCHAFFNER.
